UNITED STATES PATENT OFFICE.

HENRY F. BECHMAN, OF BATTLE CREEK, MICHIGAN, ASSIGNOR TO DUPLEX PRINTING PRESS COMPANY, OF BATTLE CREEK, MICHIGAN, A CORPORATION OF MICHIGAN.

ADJUSTABLE WEB-GUIDE.

No. 880,959.

Specification of Letters Patent.

Patented March 3, 1908.

Application filed April 29, 1907. Serial No. 370,865.

To all whom it may concern:

Be it known that I, HENRY F. BECHMAN, of Battle Creek, in the county of Calhoun and State of Michigan, have invented certain new and useful Improvements in Adjustable Web-Guides; and I hereby declare that the following is a full, clear, and exact description thereof, reference being had to the accompanying drawings, which form part of this specification.

This invention is an improvement in folding mechanisms, for web printing presses, and has particular reference to the web-guide roller which is usually located between the first-fold rolls, at the apex of the former, and the cutting cylinder or second-fold devices.

The object of the invention is to mount said roller in such manner that either end or both ends, of such roller can be adjusted both vertically and horizontally so that the said roller may be given any desired position out of true parallelism with the folding rolls or cutting cylinders as may be found necessary to prevent crawling, cracking and slipping of the web after leaving the first-fold rolls.

A great deal of trouble is experienced by pressmen in getting the web to run properly from the former to the cutting cylinders so that the latter can operate accurately. If the web is drawn too tightly over the apex of the former it is liable to be cracked or ruptured, and as the thickness of webs increases it becomes more difficult to get the web running truly to the cutting cylinders and second fold rolls. I have discovered that if the guide-roller, under which the folded webs are turned after leaving the first-fold rolls, is made adjustable, so that it can be adjusted laterally or horizontally to any desired inclination, the difficulties in handling the folded web and various thicknesses of webs in the folder can be overcome by properly adjusting this guide-roller.

The present invention therefore consists in the novel mounting of such guide-roller, and will be fully understood from the following description in connection with the accompanying drawings in which—

Figure 1 is a detail side view of a folding mechanism showing the adjustable guide-roller supports in elevation. Fig. 2 is a front view of Fig. 1, the frame being removed and certain parts being in section.

1 designates a former over which the web is led from the printing mechanism; (not

shown) at the apex of the former are located the first-fold rolls 2 as usual. From the rolls 2 the web is passed under a guide-roller 3 and then passed customarily between the cutting cylinders 4, by which the web is drawn past 60 the roll 3 and fed forward over the second-fold rolls 5 which latter are usually arranged at right angles to cutting cylinders 4. The severed sheets are tucked between rolls 5 by a blade 5^a. The aforesaid parts and the arrangement thereof are well known, and therefore they are simply diagrammatically illustrated in the drawings.

The guide-roller 3 is provided with trunnions 3^a which are journaled in castings 6 70 which are attached to upstanding arms 7^a on castings 7 by means of bolts 6^a tapped into arms 7^a and passing through slots 6^b in castings 6. A double threaded bolt 6^c is tapped into the lower end of each casting 6 and into 75 the upper side of the related casting 7, and by turning bolt 6^c, after bolt 6^a is loosened, the related casting 6 can be adjusted vertically on arm 7^a and may be rigidly secured when properly adjusted by tightening bolt 6^a. 80

The castings 7 are loosely mounted on a shaft 9^a which is supported in the main frames of the folder, and is kept from rotation by a key 9^b or other suitable means. The castings 7 are kept from longitudinal movement 85 on the shaft 9^a by means of collars 9^c, and bifurcated castings 8, said collars 9^c and castings 8 being securely pinned or fixed on the shaft 9^a, as shown.

Each casting 8 is provided with opposite 90 depending arms 8^a which extend below shaft 9^a and on opposite sides of a finger 7^c depending from the adjacent casting 7, and through the ends of arms 8^a are tapped bolts 8^c which contact with opposite sides of said 95 finger 7^c and thereby keep castings 7 from swinging or turning upon shaft 9^a; but by loosening one bolt 8^c and tightening the other, the casting 7 can be rotatably adjusted on the shaft 9^a. Thus each casting 6, and 100 the adjacent end of the roll 3, can be horizontally adjusted right or left and firmly held in any adjusted position.

As each end of the guide roller 3 is supported by similar devices upon the shaft 9^a it 105 is obvious that either end of such roller can be adjusted vertically and horizontally, and each end of the roller 3 may be adjusted similarly to or differently from, the other end, so that the roller can be given any position de- 110

sired relatively to the rolls 2 and 4,—and thus undue strain or tension on either edge of the web can be easily prevented.

While I have illustrated cylinders 4 as cutting cylinders, they also act to feed the paper forward to the second folding devices, and plain feed rolls or cylinders might be used in some makes of folding mechanisms in lieu of or in addition to the cutting cylinders 4; and 10 in some folding devices the second fold-rolls are parallel with the cutting cylinders or feeding rolls, therefore I do not wish to be restricted to the particular arrangement of cutting cylinders and second-fold rolls shown in 15 the drawings; for, as before stated, the drawings merely illustrate one kind of known folding mechanism to which the invention is applicable.

In any folding mechanism to which the invention is applied, the web can be adjusted by this roller 3 so that the variations caused by differences in number of webs folded can be easily compensated for; and so that the cutting cylinders will cut properly between 25 the margins.

Having thus described my invention what I claim as new and desire to secure by Letters Patent is:

1. In combination with folding mechanism, a web guiding roller interposed between the first-fold rolls and second-fold rolls, and means for adjusting either end of said roller independently of the other end both horizontally and vertically in different degrees.

35 2. In a folding mechanism, the combination of the first-fold rolls, cutting cylinders, and a web guide roller interposed between the rolls and cylinders; with means for vertically and horizontally adjusting either end 40 of said web guide roller in different degrees independently of its other end.

3. In combination a web guide roller, vertically adjustable castings supporting said roller, horizontally adjustable pivoted castings, supporting the first castings; means for 45 adjusting the first castings upon the second, and means for adjusting the second castings on their pivots.

4. The combination of a support, castings 50 pivotally mounted thereon, castings fixed

beside the first castings, bolts tapped through the latter castings and engaging the first castings to regulate the position of the latter, bearings mounted on the first castings, and a guide roller journaled in said bearings.

55

5. The combination of a shaft, castings rotatably mounted thereon, bifurcated castings fixed on said shaft beside the first castings, bolts tapped through the bifurcations of the latter castings and engaging the first 60 castings to regulate the position of the latter; vertically adjustable castings mounted on the first castings, and a guide roller journaled in the vertically adjustable castings.

6. In a folder, the combination of folding 65 rolls, and cutting cylinders, and a guide roller located between the first rolls and cutting cylinders; with a shaft, a pair of pivoted castings provided with upstanding arms and depending fingers, castings fixed beside the 70 first castings and provided with arms extending on opposite sides of the fingers of the first castings, bolts tapped through the arms of the castings and contacting with opposite sides of said fingers; and vertically adjustable 75 bearings for the guide roller shaft attached to the arms of the first castings.

7. The combination of a former, folding rolls, cutting cylinders, second fold-devices; and a web-guide roller located between the 80 first fold rolls and the cutting cylinders; with a shaft, a pair of castings loosely hung thereon provided with upstanding arms and depending fingers, castings fixed on the shaft beside the first castings and provided with 85 arms extending on opposite sides of the fingers of the first castings, bolts tapped through the arms of the castings and contacting with opposite sides of said fingers, and vertically adjustable castings attached to the arms of 90 the first castings by slots and bolts, and provided with bearings for the guide roller shaft, substantially as described.

In testimony that I claim the foregoing as my own, I affix my signature in presence of 95 two witnesses.

HENRY F. BECHMAN.
